UNITED STATES PATENT OFFICE.

ISAAC H. RUBIN, OF PHILADELPHIA, PENNSYLVANIA.

METHOD OF PRODUCING A FASHION-GARMENT ILLUSTRATION.

1,136,170.

Specification of Letters Patent.

Patented Apr. 20, 1915.

Application filed July 7, 1914. Serial No. 849,430.

To all whom it may concern:

Be it known that I, ISAAC H. RUBIN, a citizen of the United States, residing in the city and county of Philadelphia, State of Pennsylvania, have invented a new and useful Method of Producing a Fashion-Garment Illustration, of which the following is a specification.

My invention consists of a method of producing a fashion garment illustration or plate, the same involving a photographic copy of the fabric or material of which a garment or garments may be made, the shaping from such copy of the outlines of a member or members of a garment, the affixing of the resultant shapes on a representation of a human figure forming a partial semblance of a garment or garments, finishing said member or members to complete the semblance of the garment or garments, photographing said completed semblance and making printing surfaces therefrom for color printing and thereby producing the appearance of the exact weave, texture and color of the originally-employed fabric on the finished illustration.

The invention is satisfactorily illustrated in the accompanying drawing, but the important instrumentalities thereof may be varied, and so it is to be understood that the invention is not limited to the specific details shown and described.

Figure 1 represents a face view of what may be called a blank as the primary step of producing a fashion garment illustration embodying my invention. Figs. 2 to 5 inclusive represent successive steps of production. Fig. 6 represents a face view of the finished product of illustration.

Similar numerals of reference indicate corresponding parts in the figures.

Referring to the drawings:—In carrying out my invention, I draw, paint or otherwise prepare the representation 1 of a human being clad with the outlines of a garment of a desired fashion, the same being a black copy as shown in Fig. 1.

I photograph the particular fabric which I desire to reproduce subsequently in texture, weave and color and cut from the photograph shapes of the outlined garment,

Fig. 1, the same comprising the outlines 2 of the front of a coat, the outlines 3 of pieces of the collar thereof, and the outlines 4 of lapels thereof, together with the outlines 5 of trousers, all as shown in Fig. 2, said outlines registering with the shapes of the garments shown in Fig. 1, and then paste or otherwise secure the outlines 2 and 5 to the corresponding parts of the outlined garments, the result being shown in Fig. 3. The members 3 and 4 are also pasted or otherwise secured to the outline 2 of the coat at places corresponding to the collar and lapels of the outlined coat, the result being shown in Fig. 4. Then, I finish Fig. 4 by delineating the rest of the outlines of a coat such as the front divisional line 6, buttons, buttonholes, pockets and what may be known as trimmings, and shape-up the coat and trousers so as to impart a natural appearance to the same, thus completing the preparation of what may be called the specimen in black, as shown in Fig. 5. This specimen is now photographed and printing surfaces made therefrom for use with as many colors as desired, whereby after printing, the representation of the garments assume the appearance of the particular fabric from which the photographic subjects, Fig. 2, were taken, thus bringing out the weave, texture and color, or in other words the pattern of said fabric, as shown at 7, in Fig. 6.

Having thus described my invention what I claim as new and desire to secure by Letters Patent is:—

1. In a method of producing a fashion garment illustration, the following steps of procedure, viz., taking a copy photographically of an originally-selected fabric, forming the same into the shape or shapes of the contour and trimming of a garment or garments, affixing such shape or shapes upon the representation of a human figure in semblance of a desired garment or garments, photographing such semblance, and making printing surfaces therefrom.

2. A method of producing a fashion garment illustration embodying the photographic copying of a desired fabric or material, forming the same into the shape or

shapes of the outlines of a garment or garments, affixing such shape or shapes upon the representation of a human figure in register with such garment or garments, 5 finishing such shape or shapes in semblance of the contour and trimming of the garment or garments, photographing such sem-

blance, and making printing surfaces therefrom.

ISAAC H. RUBIN.
